UNITED STATES PATENT OFFICE

GROVER O. WARDROP, OF MUSKEGON, MICHIGAN, ASSIGNOR TO THE BRUNSWICK-BALKE-COLLENDER CO., OF CHICAGO, ILLINOIS, A CORPORATION OF DELAWARE

KICKBACK FOR BOWLING ALLEYS

Application filed July 14, 1928. Serial No. 292,881.

My invention relates to bowling alleys and particularly to kickbacks therefor.

One object of my invention is to provide a metallic reinforcement for a kickback to increase its strength and durability and prevent it from warping.

Another object of my invention is to provide a kickback with strike members, or boards, which extend over the areas of impact of bowling pins against the kickback and which may be replaced in an especially facile manner.

Other objects and advantages will appear as the description proceeds.

15 Referring to the accompanying drawings. Fig. 1 is a side elevational view of a kickback embodying my invention, a portion of a strike member and a portion of a wooden frame being broken away to show a metal frame; and

20 Fig. 2 is a sectional view on the line 2—2 of Fig. 1.

Fig. 3 is an elevational view showing the end of a bolt and the adjacent area of the 25 kickback.

The frame 1 is made of a number of pieces of wood secured together in a suitable manner, as by an adhesive, and has along its inner surface a groove 2. Flat metal strips 3 fit in and are secured in the groove 2, the strips having overlapping ends which are secured together so as to form a frame. A plurality of channel strips 4 are secured to the flat strips 3 and project inwardly from 30 the wooden frame, and a plurality of struts 5 extend from top to bottom of the metal frame, an end of each succeeding strut being secured to an end of a preceding one, the said ends being secured to the flat metallic strip 3. A pair of strike members 6, which 35 may be wooden boards or pieces of fibre or may be made of a suitable composition, fit within the wooden frame and are spaced apart by the channel strips 4 and the struts 5.

40 A plurality of retaining devices hold the strike members in position, each comprising a through bolt 7 extending through one of the strike members and received within a female bolt 8 extending through the other strike member. The head of each bolt has

a composition facing 10 and is provided with openings 11 which extend through the facing and the metal portion of the head for receiving tools by which the bolts may be turned for tightening them or for effecting the disengagement of one from the other when it is desired to remove the strike members.

When one pair of strike members becomes worn out another may readily be substituted. As the metal frame imparts rigidity to the construction and effectively prevents warping of the wood, the kickback is maintained at all times in satisfactory condition and in fact is substantially indestructible. Thus a substantial economy is effected by the invention as it renders unnecessary the replacement of kickbacks as has been done heretofore.

The invention is not limited to the specific details of the constructions illustrated and described, which may be extensively modified without departing from the spirit of the invention. A substantial range of equivalents is contemplated within the scope of the appended claims.

What I claim as new and desire to protect by Letters Patent is:

1. A kickback comprising a wooden frame having a groove in its inner face, a metal frame extending from top to bottom and end to end of said wooden frame, and comprising a flat strip received within said groove, and channel strips secured to said flat strip and projecting inwardly beyond said wooden frame, and a pair of strike members fitted within said wooden frame and extending over the areas of impact of pins against the kickback and engaging and being spaced apart by said channel strips and having their outer faces flush with the sides of said wooden frame.

2. A kickback comprising a wooden frame having a groove in its inner face, a metal frame extending from top to bottom and end to end of said wooden frame and comprising a flat strip received within said groove, channel strips secured to and extending along said flat strip and projecting interiorly from said wooden frame, and struts within said metal frame extending from top to

bottom thereof, and strike members fitted in said wooden frame and extending over the areas of impact of pins against the kickback and spaced apart by said channel strips and 5 said struts and having their outer faces flush with the sides of said wooden frame.

In testimony whereof I have hereunto subscribed my name.

GROVER O. WARDROP.
